UNITED STATES PATENT OFFICE.

CHARLES BEECKEN, OF NEW YORK, N. Y.

ROPE CLAMP.

Application filed June 14, 1922. Serial No. 568,213.

To all whom it may concern:

Be it known that I, CHARLES BEECKEN, a citizen of the United States, residing at New York, in the county of New York and State of New York, have invented certain new and useful Improvements in Rope Clamps, of which the following is a specification.

This invention relates to stationary rope clamping devices and more particularly to a novel and improved construction wherein the strands of the rope may be secured with facility and ease and without undue labor.

The primary object of my invention is to provide a novel and improved stationary rope clamping device wherein a swing clamping arm is disposed in relation with a rigid standard so as to grip the strands of the rope in addition to locking said lever arm when the same is brought into proximity with the said standard.

Another and equally important object of my invention is the provision of a stationary clamping device of the character above specified wherein the stationary standard and movable clamping arm are each provided with grooves to receive the strands of a rope, said stationary standard being provided with a pulley at its upper end which cooperates with a second pulley below the base of the standard to guide the rope when the same is unclamped and when it is being moved from one position to another upon raising or lowering an object such as a stage curtain for instance.

A continued object of my invention is the provision of a stationary clamping device which is extremely simple in construction, consisting of a minimum number of parts, easily assembled, highly efficient in operation and use, strong, durable, capable of different uses and otherwise adapted to be manufactured at an extremely low cost whereby its commercial possibilities are greatly enhanced.

I attain the above objects and others in the accompanying drawing wherein,

Figure 1 is a view partly in section showing the application of my invention.

Figure 2 is a view taken on the line 2—2 of Figure 1; and

Figure 3 is an enlarged sectional view taken along the line 3—3 of Figure 1.

Figure 4 is a detail of a portion of the grooved standard.

Referring now to the drawings wherein

like reference characters designate corresponding parts throughout the several views, 5 designates the base of a stationary casting having legs 6 secured by the bolts 7 to the flooring where the device is to be installed. 60 Rising substantially vertically from the base, I have provided a standard 8 preferably cast integral with said base, which standard gradually tapers to the reduced top 9 thereof on which a pulley or wheel 10 is mounted. 65 The base 5 of the device is slotted to receive a clamping lever 11 which also tapers toward the top 12 thereof said clamping arm 11 being pivoted as at 13 and of a height less than the length of the stationary standard 8 70 above referred to. The standard 8 is provided with a groove 14 across the length thereof on its inner side so as to accommodate the strand of rope 15 passing over the pulley 10 above referred to. At spaced intervals 75 adjacent the lower end of the standard 8, the groove is provided with outwardly formed or struck beads 16 which are adapted to grip the rope when the locking lever or arm 11 is brought into position. It will be noted 80 that the said locking lever is also provided with a groove 17 on its inner face, said groove extending throughout the length of said arm. A bead 18 is also formed in the groove 17 of the locking lever or arm 85 11 so that the upwardly extending strand 19 of the rope trained about a pulley 20 below the base 5, may be gripped and locked.

In order to properly retain the lever or locking arm 11 in position with respect to the standard 8, I have provided a bell shaped slidable clamping cup designated in its entirety by numeral 20 which is provided with a tapered slot on one side to receive the standard 8 and a second tapered slot on its 95 opposite side to accommodate the upper end of the lever arm 11. The cup 20 is also cut out as shown at 21 below the tapered portion thereof which receives the upper end 12 of the lever arm 11 so that the said cup 100 may be gripped and raised to the dotted line position as shown by Figure 1 so as to release the locking lever arm 11 when it is desired to slacken the rope. A hook 22 preferably formed integral with the base 5, 105 is also provided so that the rope may be trained thereunder and held by hand when it is desired to release the same or slacken said rope when the lever arm 11 is thrown outwardly or to its inoperative position.

While I have illustrated and described my invention with some degree of particularity, I realize that in practice various alterations therein may be made. I therefore reserve the right and privilege of changing the form of the details of construction or otherwise altering the arrangement of the correlated parts without departing from the spirit of the invention or the scope of the appended 10 claims.

Having thus described my invention what I claim as new and desire to secure by United States Letters Patent is:—

1. A stationary clamping device of the 15 class described comprising a base having a vertical standard, a clamping arm pivotally mounted on the base and movable with respect to the standard, means disposed on the inner faces of the standard and clamping arm for crimping a rope and a retaining element for said arm and standard.

2. A stationary clamping device of the 25 class described comprising a base having a vertical, tapered standard, a tapered clamping arm pivotally mounted on the base and movable with respect to the standard, spaced means formed on the opposing faces of the standard and clamping arm for crimping a rope and a slidable retaining element for 30 said arm and standard.

3. A stationary clamping device of the 35 class described comprising a base and a vertical standard formed therewith, said standard having a groove on its inner face, a clamping arm pivotally mounted on the base and movable toward the standard, said arm having a groove on its inner face and a bell shaped retaining element slidable on the standard and clamping arm for retaining 40 the latter when clamping a rope.

4. A stationary clamping device of the

class described comprising a base having a standard, a clamping arm pivoted to the base and movable toward the standard, grooves formed on the opposed inner faces of the standard and arm, said grooves being provided with crimping beads thereon for gripping a rope and a slidable retaining element on the standard for securing the upper end of the clamping arm. 50

5. A stationary clamping device of the 55 class described comprising a base having a standard, a pulley mounted on the standard, a tapered arm pivoted on the base and movable toward the standard, grooves formed on the standard and arm for receiving a rope trained over the pulley, beads within the said grooves for crimping a rope when the arm is moved toward the standard, and a releasable retaining element slidable on the standard and arm for securing the same in its clamping position.

6. A stationary clamping device of the 65 class described comprising a base, a grooved standard rising from the base, a grooved, clamping arm pivoted to the base and means for retaining said arm in its clamping position.

7. A clamping device comprising a base having a standard, a clamping member connected to the base and means for retaining said standard and member in clamping position. 70

8. A clamping device comprising a base provided with a standard, a pivoted clamping element connected to the base and movable with respect to the standard and means for retaining said standard and member in clamping position. 75

In testimony whereof I affix my signature. 80

CHARLES BEECKEN. [L.S.]
